GAS COMPRESSOR

Howell C. Cooper, Pittsburgh, Pa., assignor to S.
R. Dresser Manufacturing Co., a corporation of
Pennsylvania

Application September 4, 1931, Serial No. 561,095

5 Claims. (Cl. 230—56)

This invention relates to improvements in gas compressors, and, while of general applicability where gases and vapors are to be compressed, it finds practical application in compressors employed in the transmission of natural gas through pipe lines for distances in the order of hundreds and even of thousands of miles. The object of the invention, as it has been developed in the field indicated, is economy, both in the installation of and in the maintenance of such apparatus.

In piping natural gas across country for distances of the order indicated, it is necessary to maintain at intervals compressing stations, or booster stations, as they are called, where the flowing gas is compressed to high degree. The pressure requisite to flow diminishes along the course of the stream, and must be renewed, in order to effect transportation on commercial scale.

20 It is a practical necessity that the engines employed at the booster stations be internal combustion engines: economy of operation is determinative on that point. The compressor unit of present practice includes a pair of axially aligned power and compression cylinders. As demand increases such a unit may be built larger and heavier, until at length practical limitations in matters of weight and speed are approached, and then resort is had to multiplication of units. In 25 common practice, as many as six such units make up the working equipment of a booster station, and the stations succeed one another at intervals of about eighty miles. Further demands can then be practically satisfied only by installing more 30 booster stations; by establishing them at shorter intervals. The investment in such an installation is relatively great.

The invention is found in a compressor unit of different organization, capable of operation at 40 much higher speeds than the compressor unit of present practice alluded to above, so constructed that it will be much lighter in weight and will occupy much less space than the present-day unit of equivalent capacity; the unit of this invention 45 may be moved economically in its entirety, when no longer needed at the place of original installation, to a new location; whereas, with present-day compressors of large capacity, it is necessary to dismantle the unit preparatory to moving it. 50 and then to reassemble it in its new location, and that is a very expensive thing to do. There is incidental saving of cost in the practice of this invention: not merely in the first cost of the machine itself and in the costs of transportation 55 (matters already indicated), but also in the costs

of foundations, in erection costs, and in the cost of buildings to house the machines. And these are matters of peculiar importance in remote regions, through which pipe lines not infrequently are laid.

In the accompanying drawings, Figs. I and II are opposite end views in elevation of a compression unit of my invention; Fig. III is a view to larger scale, showing the unit in axial section, on the plane indicated at III—III, Fig. I; Fig. IV is a fragmentary view in transverse section, on the plane indicated at IV—IV, Fig. III. The moving parts are shown in Figures III and IV positioned at different stages in the cycle of operation. Figs. V—IX are fragmentary sectional views on the same plane with Fig. IV and which, when considered in connection with Fig. IV, will serve to illustrate operation; and Fig. X is a fragmentary view in section, on the plane indicated at X—X, Fig. III.

The shaft 1 of the unit, mounted in suitable bearings, is driven by the pistons 3 of a plurality of radially arranged power cylinders 2. The pistons of the so arranged group of power cylinders engage the shaft through a common 50 crank 4, as illustrated in Fig. X. Shaft 1 in turn, through a common crank 5, drives the pistons 6 of a plurality of radially arranged compression cylinders 7. The shaft 1 is provided with a fly-wheel 8. Radial arrangement in this art has 55 come to mean a grouping of three or more cylinders, spaced at equal intervals, circumferentially around the shaft. The axes of three or more cylinders so grouped necessarily lie in a plurality of radial planes (radial with respect to the shaft axis), as distinguished from the condition which obtains in case no more than one or two cylinders be employed; and in those cases the 60 axis of the one cylinder or the axes of the two lie in a single radial plane. The power cylinders which engage the crank 4 are, as here shown (Fig. II), eight in number, and the compression cylinders, engaged by crank 5, three (Fig. I); it will, however, be understood that the 65 number of cylinders in each group may be varied from three as a minimum upward. One group of power cylinders is shown in the drawings and one group of compression cylinders; and it will be understood that the number of groups of either sort may be multiplied. The shaft is shown to 70 be simple, its two parts united by the hub of the fly-wheel; it will be understood that it may be compound, and made up of a plurality of shaft parts, properly connected for rotation in 75 unison, with or without differentiation in speed. 110

Such variation will be understood to be included in the term "shaft member" used in the claims. These are matters of engineering, which need only to be mentioned in order to be understood.

5 The distinguishing feature of the radial arrangement, that the cylinder axes lie in a plurality of radial planes, is attended by this technical effect, that at every point in the range of shaft rotation tendencies to displacement under 10 inertia are positively resisted and rendered ineffective. And I have found that by adopting this radial feature in the construction and arrangement both of the power cylinders and of the compression cylinders, I am able, as otherwise I 15 should not be able, practically to attain those high speeds which render my unit economically advantageous in this art.

Each cylinder 2 with its piston 3 and associate parts may be understood to constitute an internal combustion engine of two-cycle type. It is 20 not essential to the invention that the engine be of two-cycle type; that type is chosen by way of example, merely.

The valve mechanism, for controlling the flow 25 of gas to and from the compression cylinder is mechanically operated: that is to say, it is positively driven, in response to the rotation of shaft 1. Preferably, and as here shown, the valve is 30 of rotary type. Each cylinder 7 is closed at its outer end by a valve-chest 9, within which is arranged the cylindrical rotary valve 10. The inlet and discharge passages through the valve-chest are shown in Figs. IV-IX, and the direction of flow is, in Fig. IV, indicated by arrows. 35 Rotation of valve 10 is effected from shaft 1 through the gear-shaft 11. The valve, it will be remarked, is double, in that it includes duplicate and symmetrically arranged parts: in the course of one complete rotation, therefore, it 40 repeats twice over its cycle of cooperation with the passages through the valve-chest. And the valve-driving gearing is so proportioned that the valve rotates at just one half the speed of shaft 1.

45 Rotary valves, heretofore proposed, have not gained acceptance in the practical art because of the leakage present in their operation, a feature which cannot be eliminated. For my purposes, however, a rotary valve is useful as valves of other type are not, because it is reliable at high 50 speed, and, as I have said, it is at high speed that the practical value of my arrangement is realized. The leakage inevitably present in the rotary valve may be made slight, and this slight leakage is an inconsiderable matter, in view of 55 the great practical gains incident to my characteristic high-speed operation.

60 The direction of valve rotation, as viewed in Figs. IV-IX, is clockwise, and these figures show successive positions in the course of a half rotation of the valve. During this half rotation the piston 6 within the cylinder 7 makes a complete down-and-up reciprocation, and at the completion of the half rotation a second and duplicate set of valve parts is ready to function in 65 a duplicate cycle of operation, while the piston 6 within cylinder 7 repeats its down-and-up reciprocation.

Beginning with the parts in the positions shown 70 in Fig. IV, the valve 10, turning clockwise, having previously cut off delivery from the cylinder through the valve to the discharge from the valve-chest, is now at the point of opening communication from the intake through the valve to the cylinder 7; and piston 6 has already started down 75 (in the direction indicated by an arrow) from

the upper limit of its range of reciprocation. Figs. IV, V, and VI show the range of turning of the valve while the piston operates during the suction period. At the end of the suction period, the turning valve comes to the position shown in Fig. VI. The piston on its up stroke compresses the gas. In the course of the up stroke of the piston communication through the valve to the discharge from the valve chest gradually opens and closes again, as shown in Figs. VII, VIII, and IX. (The closing actually may be deferred, and may occur just after the piston has begun its down stroke.)

80 Rotary valves have not in general been found to be satisfactory heretofore, because they may not be made tight enough; automatic reciprocating valves which, because they may be made tight, are generally preferred, are incapable of service at very high speed. I have found that, working at high speed, tightness is of less importance, and that the rotary valve is adequate.

85 In adapting the apparatus to use in the compression of gases which are inflammable—and natural gas is inflammable—provision is made, to prevent the accidental formation of an explosive mixture in the crank case. A crank case, whose walls are indicated at 12, encloses the crank 5 upon shaft 1. Into this crank case some gas necessarily will find its way by leakage past the pistons 6. The crank case is rendered practically gas-tight by the bearings for the shaft 1 which are mounted in the walls of the case; in order, however, to prevent ingress of gas to the adjacent casing chamber on the left (as seen in Fig. III), a gas seal 13 is at that point provided. 100 Through the crank-case walls, pipe connections 14 and 15 are carried, and through these gas of suitable nature (conveniently, natural gas) and at a pressure greater than atmospheric may be circulated; thus, within the casing 12 a body of 105 gas at a pressure slightly exceeding atmospheric may be maintained, filling the crank case to the exclusion of air.

110 Gas at low pressure from the pipe line enters the valve chest at the intake (from the left, Fig. IV) and gas at high pressure is delivered from the valve chest through the discharge (on the right). In this particular unit, with three compression cylinders 7, it will be understood that the stream of gas advancing through the pipe 115 line is, at the booster station, subdivided into three parts, and that one third of the whole passes through each compressor cylinder 7. It will, however, be understood that more than one such unit may be in simultaneous cooperation at a 120 booster station, and that in such case the total stream will be correspondingly subdivided.

To one heavy shaft the driving impulses of a plurality of engine elements are imparted, and the power of that shaft is applied to the total 125 volume of gas through a plurality of compressor elements, each acting upon a fraction of the whole. The economies effected by this novel compressor unit are of the nature indicated.

130 I claim as my invention:

1. In a gas compressor the combination of a rotary shaft member, a plurality of three or more engine elements radially arranged with respect to said shaft member and engaging said shaft member through a common crank, a plurality of 145 three or more compression elements, including each cylinder and a piston, radially arranged with respect to said shaft member and with the pistons of which said shaft member is through a single crank connected, a plurality of valves 150

- associated, one with each of said compression elements, and controlling the flow of gas to and from the compression elements with which they severally are associated, and means for driving the valves in response to rotation of the shaft member. 5
2. In a gas compressor the combination of a rotary shaft member, a plurality of three or more engine elements radially arranged with respect to said shaft member and engaging said shaft member through a common crank, a plurality of three or more compression elements including each a cylinder and a piston radially arranged with respect to said shaft member and with the 10 pistons of which said shaft member is through a single crank connected, a valve chest and a rotary valve within it associated with the cylinder of each compression element and means for rotating the valves in the valve chests in response to rotation of the shaft member. 15
3. In a gas compressor the combination of a shaft, a compression cylinder, a piston in said cylinder, operative connection between said shaft and said piston, a crank case enclosing said operative connection, a gas intake opening to the cylinder on the side of the piston remote from the shaft and beyond the range of piston traverse, and additional means for supplying to and for maintaining within the crank case a body of air- 20 excluding gas. 25
4. In a gas compressor the combination of a shaft, a crank borne by the shaft, a compression element including a cylinder and a piston radially 30
- arranged with respect to said shaft, the said piston being operatively connected to said shaft, a crank case enclosing said crank and crank connections and the adjacent portions of the shaft and the proximate end of the said cylinder, means for admitting gas to and permitting discharge of gas from the remote end of said cylinder, such means being arranged beyond the range of piston traverse, and additional means arranged on the opposite side of the piston and beyond its range of traverse in opposite direction for supplying to and for maintaining within the crank case a body of air- 35 excluding gas. 40
5. In a gas compressor the combination of a shaft, a crank borne by the shaft, a plurality of compression elements grouped radially about the shaft, each including a cylinder and a piston, all of the pistons of the said elements being operatively connected to the said crank which serves them in common, means arranged beyond the outer ends of piston traverse for admitting gas to and permitting the discharge of gas from the ends of the cylinders remote from the shaft, a crank case enclosing the said crank and crank 45 connections and the adjacent portions of the shaft and the proximate ends of the cylinders of the compression elements, and means arranged beyond the inner ends of piston traverse for maintaining within the crank case a body of air- 50 excluding gas. 55

- associated, one with each of said compression elements, and controlling the flow of gas to and from the compression elements with which they severally are associated, and means for driving the valves in response to rotation of the shaft member. 5
2. In a gas compressor the combination of a rotary shaft member, a plurality of three or more engine elements radially arranged with respect to said shaft member and engaging said shaft member through a common crank, a plurality of three or more compression elements including each a cylinder and a piston radially arranged with respect to said shaft member and with the 10 pistons of which said shaft member is through a single crank connected, a valve chest and a rotary valve within it associated with the cylinder of each compression element and means for rotating the valves in the valve chests in response to rotation of the shaft member. 15
3. In a gas compressor the combination of a shaft, a compression cylinder, a piston in said cylinder, operative connection between said shaft and said piston, a crank case enclosing said operative connection, a gas intake opening to the cylinder on the side of the piston remote from the shaft and beyond the range of piston traverse, and additional means for supplying to and for maintaining within the crank case a body of air- 20 excluding gas. 25
4. In a gas compressor the combination of a shaft, a crank borne by the shaft, a compression element including a cylinder and a piston radially 30
- arranged with respect to said shaft, the said piston being operatively connected to said shaft, a crank case enclosing said crank and crank connections and the adjacent portions of the shaft and the proximate end of the said cylinder, means for admitting gas to and permitting discharge of gas from the remote end of said cylinder, such means being arranged beyond the range of piston traverse, and additional means arranged on the opposite side of the piston and beyond its range of traverse in opposite direction for supplying to and for maintaining within the crank case a body of air- 35 excluding gas. 40
5. In a gas compressor the combination of a shaft, a crank borne by the shaft, a plurality of compression elements grouped radially about the shaft, each including a cylinder and a piston, all of the pistons of the said elements being operatively connected to the said crank which serves them in common, means arranged beyond the outer ends of piston traverse for admitting gas to and permitting the discharge of gas from the ends of the cylinders remote from the shaft, a crank case enclosing the said crank and crank 45 connections and the adjacent portions of the shaft and the proximate ends of the cylinders of the compression elements, and means arranged beyond the inner ends of piston traverse for maintaining within the crank case a body of air- 50 excluding gas. 55
